To all whom it may concern:

Be it known that I, ETIENNE GUIRAUD, of New York, in the county and State of New York, have invented a new and original Design for a Carpet, of which the following is a specification.

The accompanying photographic illustration represents a face view of my newly-designed carpet.

This invention relates to a new and original design for carpets, oil-cloths, and similar fabrics.

It consists in the new ornamentation, configuration, and grouping of the figures, hereinafter more fully described.

Upon the background of the carpet, which is preferably made of different colors, is represented a large scroll, A, having three branches, *a*, *b*, and *c*. The branch *a* terminates in a bouquet, *d*. The central largest branch, *b*, is snail-shaped and terminates in a flower, *e*. A rich bouquet, *f*, is placed at the side of this branch and connects therewith. The branch *c* terminates in a bouquet, *g*. Upon the background is furthermore represented a conspicuous floral group, B, in which a ternate leaf, *h*, and incised leaf *i* and a group of palm-leaves, *j*, are prominent. A cluster of flowers in compact panicles, *k*, and a small tree-like ornament, *l*, are also represented in this group. D

is a large scroll traversing the group B and terminating in a volute, *m*.

I claim—

1. The design for a carpet, consisting of the scroll A, having branches *a*, *b*, and *c*, substantially as shown.
